UNITED STATES PATENT OFFICE.

MICHAEL LAWRENCE MERY, OF CHICO, CALIFORNIA.

EXPLOSIVE ENGINE.

SPECIFICATION forming part of Letters Patent No. 543,157, dated July 23, 1895.

Application filed February 7, 1895. Serial No. 537,648. (No model.)

To all whom it may concern:

Be it known that I, MICHAEL LAWRENCE MERY, a citizen of the United States, residing at Chico, Butte county, State of California, have invented an Improvement in Explosive Engines; and I hereby declare the following to be a full, clear, and exact description of the same.

My invention relates to the class of explosive engines, and particularly to those termed "double-acting"—that is, those which explode alternately in each end of the cylinder or explosion-chamber connected therewith.

My invention consists in the novel details of construction, arrangement, and combination which I shall hereinafter fully describe and specifically claim.

The object of my invention is to provide a double-acting explosive engine, simple in its construction of parts, efficient and accurate in its explosions, and capable of easy and perfect adjustment.

Referring to the accompanying drawings for a more complete explanation of my invention, Figure 1 is a plan view. Fig. 2 is a detail of the sparking device. Fig. 3 is a vertical section on the line $x-x$ of Fig. 1. Fig. 4 is a section on line $y-y$ of Fig. 1. Fig. 5 is a perspective view of the means for operating the sparking device and regulating the admission of the explosive mixture. Fig. 6 is a view of the means for operating and regulating the exhaust-valves.

A is a cylinder in which is mounted and adapted to operate a suitable piston, of which B is the rod which operates through one end or head of the cylinder in a suitable stuffing-box, (represented by C,) the details of construction of said stuffing-box being unnecessary to describe further than to mention that both it and the cylinder shall be water-jacketed in the usual manner, or in any proper manner as is common and necessary with double-acting explosive engines.

On one side of the cylinder, at each end thereof, are the firing or explosion chambers D, in which are mounted the inlet-valves E, which said valves are of the ordinary puppet type and are arranged to rise up inwardly to open their ports under the sucking action of the engine, whereby the inlet of the explosive charge or mixture is effected automatically. With the

ports which these valves control the gas-pipe F communicates, said pipe having a suitable connection in which are fitted properly controlling-cocks f for the air and gas mixture.

The stems e of inlet-valves E extend downwardly and are provided with springs e', whereby their return to their seats is insured.

Within each explosion-chamber is mounted the fixed electrode G, which consists of a spring-strip mounted on edge and having its end bent at a slight inclination, as shown. This electrode is mounted in a suitable manner in the explosion-chamber and is properly insulated therefrom in order to provide for the proper electrical connection. Being mounted on edge, it is sufficiently rigid to withstand any bending tendency due to gravity under any heat to which it may be subjected.

The movable electrode H within the explosion-chamber consists of a contact-point, which is also bent at an inclination and overlaps the inclined end of the stationary electrode G, so that when the movable electrode H rises it passes in contact with the inclined end of the fixed electrode on one side, and produces the electric spark as it leaves or parts with said electrode on its upward movement, and comes down past the stationary electrode on its other side, but does not on this downward movement produce a spark, for the reason that the battery-circuit is then broken, as I shall presently describe.

The movable electrode H has a stem h which extends downwardly and is adapted to be raised by means of the end of the rocking lever I coming in contact with it. The contact of this lever end and the stem h of the movable electrode is effected by means of an end piece i, which is secured to and electrically-insulated from the lever I, said piece having a horizontally-slotted extremity, as shown at i', within which is seated a cross-pin h' on the extremity of the stem h, whereby a sufficiently-free connection is effected between the two to provide for the following adjustment, namely: The time of contact between the lever I and the stem h may be varied and regulated by means of a set-screw i² under the end i, and it may be set up or down to come in contact with the end of the stem h sooner or later, as may be desired.

In order to keep the stem h from twisting

- or turning its lower end is fitted in a guide block h^2 , which is seated in the end i of the lever I. Upon the block h^2 is a contact-pin h^3 , which is adapted on the upward movement 5 of the stem h to make electrical contact with a piece or spring h^4 , thereby completing the battery-circuit when said contact is made. It will therefore be seen that on the upward movement of the electrode H the battery-circuit will be closed by the contact of the pin h^3 and the spring h^4 , and the spark will be effected by the separation of the two electrodes in the explosion-chamber. On the downward movement, however, the pin h^3 drops instantly 10 and rapidly away from the spring h^4 , so that the battery-circuit is opened and there is no spark generated, thus saving the battery strength as well as providing for but a single explosion, as required.
- 20 The stem h of the movable electrode H in passing out through the wall of the explosion-chamber is insulated therefrom by means of a sleeve h^5 , freely encircling the stem h and fitted within the downwardly-extending housing or flange d of the explosion-chamber wall, the two being separated by insulating material (represented by d') and held tightly together by means of a nut d^2 and a gland d^3 .
- 25 The lever I, by which the movable electrodes at each end are alternately operated, is a rocking one, being mounted by a central hub i^3 upon a pivotal shaft J, extending cross-wise under the engine. The hub i^3 has a downwardly-extending crank i^4 , with which a rod i^5 is connected, said rod being operated by a suitable eccentric upon a counter-shaft of the engine, unnecessary herein to show. The position of the rocking lever I and its consequent effect upon the movable electrodes 30 at each end, both in time and amount, is varied and regulated by means of an intervening eccentric-sleeve K, mounted and adapted to oscillate upon the pivot-shaft J, the hub i^3 of the lever I being mounted upon said eccentric-sleeve K. Now it will be seen that by 35 turning the eccentric-sleeve K to different positions the pivotal center of the lever I will be raised or lowered and its operation varied as desired.
- 40 50 The eccentric-sleeve may be operated by any suitable means, and I have here shown for the purpose what I deem the best means—namely, an extension-arm k extending downwardly from the sleeve and having mounted in one side of it a spring-controlled latch-pin k' , which is adapted to engage with any of a series of sockets j' in a collar j on the end of the pivotal shaft J.
- 45 On the other side of the cylinder and at 60 each end thereof are the exhaust-chambers L, in which are mounted the exhaust-valves M. Each valve has a downwardly-extending stem m provided with a controlling-spring m' , and these stems are operated by the contact of the ends of the rocking-lever N mounted upon the other end of the pivot-shaft J, said lever having a downwardly-extending crank n , to

which is attached a connecting-rod n' , which is operated by an eccentric on the counter-shaft of the engine, unnecessary herein to 70 show. The contact of the ends of the lever N with the stems m of the exhaust-valves M is alternate and is adjusted and regulated by means of set-screws n^2 .

To regulate or govern the engine by controlling the operation of its exhaust-valves M I have the following controlling or governing mechanism: Pivoted at o to the exhaust-chamber walls is a pawl O, one for each exhaust-valve. The extremity of this pawl extends into the passage-way of the stem m of the exhaust-valve, and in the normal position of the pawl it is out of engagement with said stem; but if the point of the pawl be lowered it is adapted to slip under and engage with a shoulder m^3 on the stem m , thereby holding the valve wide open and checking the operation of the engine. This movement of the pawls is effected by means of oppositely-extending arms o' of said pawls, the meeting extremities of which lie upon crank-pins p on an oscillating-disk P. This disk is mounted on a shaft p' , the other extremity of which is provided with a pendulum p^2 , and said shaft is journaled within a sleeve n^3 on the upper 95 end of a crank n^4 , which rises from the central hub of the rocking lever N. Now, when the speed of the engine increases, the vibration of the pendulum p^2 is increased, thereby rocking the disk P and elevating its crank-pins p , which has the effect of raising the handles o' of the pawls O and thereby depressing said pawls and causing them to come to engagement under the shoulders m^3 of the valve-stems. As soon as the speed decreases 100 and the vibration of the pendulum is reduced, the handles o' will be lowered by their own weight and the pawls will move from their engagement with the valve-stems.

To regulate the admission of the charge of explosive mixture I have the following mechanism: Pivoted at q are the bell-crank levers Q, the extremity of the vertical arm of each of which is provided with a series of notches q' removed, by their construction, to varying 110 distances from the stems e of the inlet-valves E. The lower ends of the valve-stems e are provided with a nut or stop e^2 , and it will be seen that if the vertical arm of the lever Q be swung toward the valve-stem one or another of its notches q' will be thrown in the path of the movement of the nut e^2 of the stem, and said stem will thereby be arrested at different points, according to the position of the particular notch of the series which 115 engages the nut, and thus the inlet-valve will be regulated and properly adjusted in its rise.

The bell-crank or elbow levers Q are operated automatically by the following mechanism: Upon a standard j^2 , rising from the collar j on the end of the pivotal shaft J, is mounted in suitable slides therein (here shown as a dovetailed recess) a plate R, which has projecting from it a pin r , which plays up and

down in a slot j^3 in the standard j^2 . With this pin is connected a rod S, which may be supposed to extend to and to be raised and lowered by the operation of a suitable governor, unnecessary herein to show. Upon the top of the plate R is an arm r' , which extends under and is adapted to come in contact with the ends of the horizontal arms of the bell-crank levers Q, said contact being an adjustable one by means of a screw q^2 . As the speed of the governor increases, it is intended that the rod S shall be forced downwardly, thereby forcing down plate R and its arm r' . This will allow the horizontal arms of the levers Q, which said arms are heavier than the vertical arms, to cause the latter to swing toward the valve-stems and engage and limit them, as heretofore described. As the speed of the engine decreases the rod S is elevated and the plate R likewise rises, and its arm r' , operating under the horizontal arms of levers Q, will withdraw their vertical arms and allow the valves E to work freely.

A great difficulty in explosive engines is the drawing back into the cylinder of the exhausted products of the explosion through the open exhaust-valves which are alternately held open. To remedy this and to provide for the indrawing through said valves of fresh air rather than of the products of explosion previously exhausted, I have provided the following construction: The exhaust-chambers L are connected by branches L', which join in a common exhaust L². In these branches, opposite their point of junction with the pipe L², I seat an inwardly-opening valve L³, controlling a port which communicates with the exterior air. I have found that upon holding the exhaust-valves open and thereby creating a back suction through them the fresh air will lift the valve L³ and will be drawn through the branches L' into the cylinder with very little, if any, of the exhausted products of explosion. By this means I cleanse the cylinder and help to keep it cool.

Having thus described my invention, what I claim as new, and desire to secure by Letters Patent, is—

1. In an explosive engine, the sparking apparatus, consisting of the fixed electrode, mounted upon edge and having its outer extremity only bent to an inclination, and the movable electrode, also on edge and correspondingly inclined to the bent extremity of the fixed electrode, whereby it is adapted to pass up and in contact with one side of the fixed electrode, and down on the opposite side.

2. In an explosive engine, the sparking apparatus, consisting of a fixed electrode mounted upon edge and having its outer extremity only bent to an inclination, a movable electrode adapted to reciprocate past the fixed electrode and make and break contact therewith, and a means independent of the electrodes for closing the battery circuit when the movable electrode passes in one direction and

opening it on the return movement comprising a contact on the stem of the movable electrode and a fixed contact in the battery circuit.

3. In an explosive engine, the sparking apparatus consisting of the fixed electrode, mounted upon edge and having an inclined extremity, and the movable electrode, correspondingly inclined to the extremity of the fixed electrode, whereby it is adapted to pass up and in contact with one side of the fixed electrode and down on its other side, and a means for closing the battery circuit on one movement of the movable electrode and opening it on the return movement, consisting of a contact on the stem of the movable electrode, and a fixed spring in the battery circuit, with which the contact makes and breaks electrical connection.

4. In a double acting explosive engine, a fixed and a movable electrode within each explosion chamber, in combination with means for operating the movable electrodes alternately consisting of a pivoted rocking lever having its ends adapted to alternately come in contact with the ends of the movable electrode, and a means for regulating the rocking lever consisting of an eccentric sleeve on which said lever is pivoted.

5. In a double acting explosive engine, a fixed and a movable electrode within each explosion chamber, in combination with means for operating the movable electrodes, consisting of a pivoted rocking lever, having its ends adapted to alternately come in contact with the ends of the movable electrode, the eccentric sleeve on which said lever is pivoted and by which it is regulated, and the means for adjusting said sleeve consisting of its arm having the spring-controlled locking pin and the collar on the pivotal shaft having the sockets with which the pin engages.

6. In combination with the movable electrodes of an explosive engine, said electrodes having projecting stems, a rocking lever having the end pieces with horizontal slots in which the ends of the electrode stems are secured, and the steadyng blocks on said stems fitted in the ends of the rocking lever.

7. In combination with the movable electrodes of an explosive engine, said electrodes having projecting stems, a rocking lever having the end pieces with horizontal slots in which the ends of the electrode stems are adjustably secured by a cross pin, and the set screws for adjusting the contact of the lever with the stems of the movable electrodes.

8. In an explosive engine, the combination of the explosion chamber wall having a downwardly extending conical flange d, a conical sleeve fitting within said flange, an insulating material between the sleeve and flange, a movable electrode having a stem passing through the sleeve, a nut d² threaded on the lower portion of the sleeve and bearing up under the flange and a gland engaging said sleeve, substantially as herein described.

9. In an explosive engine and in combination with a valve therein having a stem, a pawl for engaging said stem to regulate the operation of the valve, and a means dependent upon the speed of the engine for operating the pawl, consisting of a rocking arm, a shaft pivoted in said arm and having a pendulum upon one end and a disk upon the other end, said disk having a pin upon which the handle of the pawl rests.
10. In an explosive engine, the exhaust valves thereof, having reciprocating stems, with shoulders, in combination with pivoted pawls adapted to make and break engagement with said shoulders for holding open and relieving the valves, and a means, dependent upon the speed of the engine for operating said pawls, consisting of a rocking lever by which the valves are normally operated, an arm rising from said lever, a shaft pivoted in the upper end of the arm and having a pendulum upon one end and a disk upon the other end of said shaft having a pin upon which the handles of the governing pawls rest.
11. In an explosive engine, the inlet valves thereof, in combination with the means for controlling them to regulate the charge admitted, consisting of the pivoted bell crank levers having the series of notches adapted to be thrown in the path of movement of the valve stems to limit said movement at different distances, and means, comprising a vertically movable device operated by a governor and an extension from the device to op-

erate the lever, dependent upon the speed of the engine for swinging said bell crank levers.

12. In an explosive engine, the inlet valves thereof, in combination with the means for controlling them to regulate the charge admitted, consisting of the pivoted bell crank levers having the series of notches adapted to be thrown in the path of movement of the valve stems to limit said movement at different distances, and means, dependent upon the speed of the engine for swinging said bell crank levers, consisting of a vertically movable plate adapted to be operated by a suitable governor, and an arm upon said plate adapted to operate under the arms of the bell crank levers.

13. In an explosive engine, the branches from the exhaust chambers thereof, uniting in a common exhaust pipe and the inwardly opening valve in said branches whereby fresh air is drawn into the engine when the exhaust valves are opened.

14. In an explosive engine and in combination with its exhaust valve and exhaust pipe, an inwardly opening valve in said pipe beyond the exhaust valve through which fresh air may be drawn into the cylinder through the open exhaust valve.

In witness whereof I have hereunto set my hand.

MICHAEL LAWRENCE MERY.
